US0D1063539S

(12) United States Design Patent (10) Patent No.: US D1,063,539 S
(45) Date of Patent: * Feb. 25, 2025

(54) SPORT BOTTLE

(71) Applicant: Dongguan Oumeng Houseware Products Co., Ltd, Dongguan (CN)

(72) Inventor: Jinsheng Xu, Dongguan (CN)

() Term: 15 Years

(21) Appl. No.: 29/938,560

(22) Filed: Apr. 22, 2024

(30) Foreign Application Priority Data

Apr. 2, 2024 (CN) 202430179958.6

(51) LOC (15) Cl. 07-01

(52) U.S. Cl.

USPC D7/510; D7/396.2

(58) Field of Classification Search

USPC D7/507, 509-511, 533, 536, 543, 300.1, D7/300.2, 619.1, 391, 392.1, 396.1, D7/396.2, 629, 900; D3/202; D9/503, D9/435

CPC A63F 2009/0058; A47G 19/2205; A47G 21/18; A47J 41/00; B65D 1/00

See application file for complete search history.

(57) CLAIM

The ornamental design for a sport bottle, as shown and described.

DESCRIPTION

FIG. 1 is a perspective view of our new design for a sport bottle;

FIG. 2 is another perspective view thereof;

FIG. 3 is a front elevation view thereof;

FIG. 4 is a back elevation view thereof;

FIG. 5 is a left-side view thereof;

FIG. 6 is a right-side view thereof;

FIG. 7 is a top plan view thereof; and,

FIG. 8 is a bottom plan view thereof.

The broken lines depict portions of the sport bottle that form no part of the claimed design.

1 Claim, 8 Drawing Sheets
